LOUIS OFFERMAN, OF BROOKLYN, NEW YORK

CIGARETTE HOLDER

Application filed March 11, 1930. Serial No. 434,842.

This invention relates to cigarette holders, and more particularly to cigarette holders of the table or desk type.

A known type of cigarette holder comprises a cylindrical casing which is closed at the bottom and open at the top, and within which there is slidably mounted cigarette holding and ejecting mechanism including a circular tray and radial vanes or partitions. A cover 10 for the cylindrical casing is mounted above the partitions and is provided with a handle, by means of which the cover and tray may be elevated partially out of the casing, thereby making the cigarettes therein accessible.

In the manufacture of such cigarette holders it is necessary to obtain a very precise and accurate fit between the movable member including the tray and radial vanes and the interior walls of the casing, for, on the one hand, clearance is necessary in order to permit free movement, and, on the other hand, the clearance must be made slight in order to prevent the movable tray from tipping to an angle which might cause binding or chattering. One object of the present invention is to improve such a cigarette holder in order to make the motion or reciprocation of the movable portion thereof free and yet definitely guided. This I accomplish by providing the casing with an upright post, preferably located centrally thereof, and providing the movable portion of the cigarette holder with a sleeve which is freely reciprocable on the post. With this arrangement considerable clearance may be provided between the casing and the tray and the vanes of the movable portion of the holder, thereby making it possible to manufacture the device with greater ease and cheapness.

It has already been mentioned that access is gained to the cigarettes in the holder by manually lifting the cover and cigarette ejecting tray. A further object of the present invention is to dispense with this manual lifting operation, so that the holder may be opened automatically and left open for so long as may be desired. To this end resilient means are provided which tend to elevate the tray and cover of the holder. Suitable additional means are provided for locking the

cover in closed position against the tension of the resilient means.

Another object of the present invention is to devise a cigarette holder embodying both of the foregoing features, that is, the central guide or post and the automatic ejection of the cigarettes. For this purpose it is merely necessary to provide a helical spring surrounding the post and located between the tray and the bottom of the casing, so that the spring is compressed when the cigarette holder is closed.

Still another object of my invention resides in the provision of suitable locking means for keeping the holder closed, and manually operable releasing means for permitting the holder to open. For the sake of accessibility, the said releasing means is located at the top of the holder above the cover of the casing, while the locking means is conveniently located relative thereto by being made of mating elements located at the top of the reciprocable sleeve and the upright post.

A still further object of the present invention is to make the cigarette holder capable of a dual function so that it may be used as an ash tray as well as a cigarette holder, and for this purpose the cylindrical casing so far described is mounted upon a base suitably shaped to constitute an ash tray.

To the accomplishment of the foregoing and such other objects as will hereinafter appear, my invention consists in the cigarette holder elements and their relation one to the other, as hereinafter are more particularly described and sought to be defined in the claims. The specification is accompanied by a drawing which shows the preferred embodiments of my invention, and in which:

Fig. 1 is a perspective view of the cigarette holder;

Fig. 2 is a vertical section taken through the axis of the same;

Fig. 3 is a horizontal section taken in the plane of the line 3—3 in Fig. 2; and

Fig. 4 is a horizontal section taken in the plane of the line 4—4 in Fig. 2.

Referring to the drawing, the cigarette holder comprises generally a stationary cas-

ing A, within which there is reciprocably mounted a movable cigarette holding and ejecting assemblage B, which is constantly urged to an elevated position by resilient means C. The movable assemblage B may be locked in depressed position by suitable locking and release means D. The entire holder may, if desired, be mounted upon an enlarged base E shaped to act as an ash receiver.

Considered more in detail, the casing A is preferably cylindrical in shape and closed at its lower end by a preferably arcuate wall 2. The upper end of the casing is open, and the edge thereof is preferably rolled over as at 4 to form a bead. An additional bead 6 may be formed slightly below the upper edge of the casing, which is decorative and possesses an additional function which will be described subsequently.

An upright rod or post 8 is centrally located within the casing A. When the holder is combined with an ash tray, as in the present case, the post 8 may extend downwardly through the holder and into a pedestal 10 formed at the center of the tray E, and the anchorage of the post to the tray may also serve to hold the casing A in place.

The movable portion B of the holder comprises a tube or sleeve 12 which slides freely upon the post 8. A cigarette holding and ejecting tray 14 is fixed to the lower end of the sleeve 12, while a cover 16 for the casing A is fixed to the upper end of the sleeve 12. The tray 14 may be provided with radial vanes or partitions 18 which serve to keep the cigarettes in a nearly vertical position, and which further make it possible to separate different brands of cigarettes within the holder. It should be noted that unlike previous cigarette holders of this type, the tray 14 and the partitions 18 need not be carefully made and assembled to closely fit the casing A, for the movement of the assemblage B is guided by the fit of the post 8 and the sleeve 12.

As so far described, the holder might be opened manually and closed by gravity. However, I have devised an arrangement which is found far more convenient in practice because the holder may be automatically opened by resilient means C. As is obvious from the drawing, this may comprise simply a helical spring preferably surrounding the post 8 and located between the tray 14 and the bottom of the cylindrical casing. The spring is preferably made of such a length that the movable assembly B is only partially elevated to a height such that the cigarettes are readily accessible and yet are confined sufficiently to prevent them from falling out of the holder.

The permissible upward movement of the ejector assembly B may be positively limited to prevent the assembly from being lifted

entirely out of the casing by the cooperation between a resilient wire ring 20, held in place by the bead 6, previously referred to, and recesses 22 cut in the vertical edges of the partitions 18. The lower portions of the partitions 18 extend fairly close to the inner wall of the casing A, whereas the upper portions are stepped inward or terminate at a smaller diameter, which clears the inner diameter of the retaining ring 20. In this manner the assembly B can not be raised beyond the point determined by the contact of the stepped edges of the partitions 18 with the ring 20. If it is desired to disassemble the holder, the retaining ring 20 may first be released and removed, after which the movable portion of the holder may readily be lifted from the casing.

To close the holder the cover is depressed against the pressure of the spring C, and locking means is provided to hold the same in closed position. The locking means is manually releasable, and this release I prefer to locate at the top of the holder for ready accessibility. The locking mechanism comprises means 30 on the movable assembly B cooperating with mating means 32 on the post 8. The means 32 is simply an annular groove cut in the post, while the means 30 in the present instance comprises a pair of fingers resiliently urged together by a spring U-shaped member D. The upper end of the post 8 may be rounded or tapered as at 34 in order to readily separate the fingers 30 when the cover of the holder is depressed. It will be clear that when the holder is entirely closed the fingers 30 pass the upper end 34 of the post 8 and enter the groove 32, thereby retaining the holder in closed position.

Release of the locking means is obtained by sideward movement of the U-shaped member D in the following manner. The upper end of the sleeve 12 is finished with a suitable decorative cap 40 having a flange 42. At diametrically opposed points the flange 42 is cut away to form cam surfaces 44, and the legs of the U-shaped release member D are disposed within these cam surfaces. When the member D is in its normal erect position the legs thereof may come together sufficiently to permit the fingers 30 to enter the groove 32, and so to keep the holder in closed position. A sideward movement of the member D causes the legs thereof to bear against the cam surfaces 44, which spread or separate the legs slightly and thereby cause the fingers 30 to leave the groove 32, and so to permit the holder to open. This cam release mechanism is so designed that an exceedingly slight sideward pressure or touch on the member D releases the holder and permits the spring C to raise the cigarettes into the open or accessible position. There is no tendency for the holder to tip over during the releasing movement, and this is particularly true when the

holder is provided with an enlarged base such as the base E here illustrated.

Additional use is made of the base E in the present instance by shaping it concavely upward so that it may be used as an ash tray.

The construction, mode of operation, and the many advantages of my novel cigarette holder will for the most part be apparent from the foregoing description thereof. The movable portion or cigarette ejecting assembly is smoothly and accurately guided by the fit of the sleeve on the stationary post within the casing of the holder, so that an accurate fit between the cigarette ejecting tray and partitions within the casing is unnecessary. The holder may be opened automatically by spring action and may be left in the open position until those present all have had an opportunity to obtain a cigarette. Accidental removal of the cigarette ejecting assembly entirely out of the casing is guarded against. The locking and release mechanism is exceedingly simple and operable with very slight pressure. The holder may be mounted upon an enlarged base to increase its stability, and this base is preferably suitably shaped to act as an ash tray.

It should be understood that the various features of my invention, such as the central guide for the movable portion of the holder and the automatic elevation of the movable portion of the holder, may be applied and utilized separately as well as in combination, and further that in either case they may be applied to a cigarette holder which is not cylindrical in configuration.

It will be apparent that while I have shown and described my invention in the preferred form, many changes and modifications may be made in the structure disclosed without departing from the spirit of the invention, defined in the following claims.

I claim:

1. A cigarette holder comprising a casing, a post located therein, a sleeve reciprocably mounted on said post, a tray fixed to the lower end of said sleeve, a cover fixed to the upper end of said sleeve, resilient means tending to elevate said sleeve, and mechanism for locking the sleeve in depressed position comprising mating means on the post and on the sleeve.

2. A cigarette holder comprising a cylindrical casing, a post centrally located therein, a sleeve reciprocably mounted on said post, a tray fixed to the lower end of said sleeve, a cover fixed to the upper end of said sleeve, resilient means tending to elevate said sleeve, and mechanism for locking the sleeve in depressed position comprising an annular groove in the upper end of the post, and manually releasable resilient means mounted on the upper end of the sleeve above the cover for mating with said groove.

3. A cigarette holder comprising a cylind-

rical casing, a post centrally located therein, a sleeve reciprocably mounted on said post, a tray fixed to the lower end of said sleeve, a cover fixed to the upper end of said sleeve, resilient means tending to elevate said sleeve, mechanism for locking the holder in closed position comprising mating means on the post and on the sleeve, and manually operable means mounted above the cover for releasing the locking mechanism.

4. A cigarette holder comprising an ash tray, a cylindrical casing mounted thereon, a post centrally located in the casing, a sleeve reciprocably mounted on said post, a tray fixed to the lower end of said sleeve, a cover fixed to the upper end of said sleeve, resilient means tending to elevate said sleeve, mechanism for locking the holder in closed position comprising mating means on the post and on the sleeve, and manually operable means above the cover for releasing the locking mechanism.

5. A cigarette holder and dispensing device comprising a stationary part including a cylindrical casing and a post centrally located therein, and a vertically reciprocable part including a sleeve reciprocably mounted on the post, a circular cigarette holding and ejecting tray mounted at the lower end of the sleeve, radial partitions mounted on the tray and sleeve and forming cigarette holding compartments, and a cover mounted at the upper end of the sleeve and spaced from the tray and partitions in order to permit free access to the cigarettes supported by the tray, resilient means surrounding the post between the tray and the bottom of the casing and tending to elevate and keep elevated the tray and cover to make the cigarettes accessible, means to limit the elevation of the movable part of the cigarette holder including an annular outwardly pressed groove near the top of the cylindrical casing, stops formed on the radial partitions, and a stop ring resiliently expanded into and supported by the aforesaid annular groove, and releasable mating means mounted on the stationary and reciprocable parts of the cigarette holder for locking the tray and cover in closed position against the resilient means.

Signed at New York in the county of New York and State of New York this 10th day of March, A. D. 1930.
